DESIGN FOR A ROTATABLE SPIT BARBECUE

Lewis C. Hufford and Landon R. Gray,
Redondo Beach, Calif.

Application November 27, 1944, Serial No. 116,571

Term of patent 3½ years

(Cl. D81—10)

To all whom it may concern:

Be it known that we, Lewis C. Hufford and Landon R. Gray, citizens of the United States, residing in Redondo Beach, in the county of Los Angeles and State of California, have invented a new, original, and ornamental Design for a Rotatable Spit Barbecue, of which the following is a specification, reference being had to the accompanying drawing, forming part thereof.

Fig. 1 is a front elevational view of a rotatable spit barbecue, showing our new design;

Fig. 2 is a top plan view thereof;
Fig. 3 is an end elevational view thereof; and
Fig. 4 is a rear elevational view of the barbecue.
The dominant features of the design reside in the portions shown in full lines.

We claim:

The ornamental design for a rotatable spit barbecue, substantially as shown and described.

LEWIS C. HUFFORD.
LANDON R. GRAY.
